UNITED STATES PATENT OFFICE.

WILLIAM B. RUNK, OF SHELTON, CONNECTICUT, ASSIGNOR TO ROBERT N. BASSETT COMPANY, INCORPORATED, OF SHELTON, CONNECTICUT, A CORPORATION OF CONNECTICUT.

BUTTON-CLASP.

1,332,759.

Specification of Letters Patent.

Patented Mar. 2, 1920.

Application filed November 22, 1918. Serial No. 263,702.

To all whom it may concern:

Be it known that I, WILLIAM B. RUNK, a citizen of the United States, residing at Shelton, in the county of Fairfield and State 5 of Connecticut, have invented a certain new and useful Improvement in Button-Clasps, of which the following is a specification.

My invention relates to metal mountings for running webbing of the class wherein 10 two members are hinged together by means of pintles journaled in bearings, and its object is to produce a device of this character in which the constituent parts can be assembled by hand thereby dispensing with 15 the press or machine generally employed during the assembling operation.

For the purpose of enabling the invention to be better understood by those skilled in the art I have embodied the same in the 20 button clasp herein illustrated and described which is distinguished from other button clasps in that one side of the bearing is cut away for the passage of one of the pintles during the assembling operation.

25 I attain this and other objects of my invention in the device set forth in the following description and accompanying drawings in which like reference characters refer to corresponding parts.

30 In the drawings:

Figure 1 is a rear view of a button clasp carried by the lower extremity of a supporting webbing;

Fig. 2, a central vertical section taken on 35 line $x-x$ in Fig. 1, and

Figs. 3 and 4, rear views showing the position of the parts during the process of assembling.

The button clasp, which is shown depending 40 from a fold in the extremity of the supporting strap A, consists of an attaching loop B, a button loop C, and a button tab or tape D which carries a button E at its lower extremity. The button loop C, which is connected to the lower side of the loop B by a bearing sleeve F projecting from the upper side thereof, is provided with a bridge G and has the sides of its lower extremity contracted to engage the shank of the button E.

50 The device thus far described is one of the common forms of button clasps well known in the art and is merely disclosed for the purpose of showing how my invention is applied. The attaching loop B is formed 55 out of wire the extremities of which termi-

nate in the pintles 2, 2'. The portion of the loop immediately beyond the outer ends of the pintles are provided with offset members or shoulders 3, 3'. The button loop C is made out of the sheet metal, and is provided with a projecting strap at its upper extremity which is curled to form a sleeve member or pintle bearing F. This pintle bearing is cut away on its under side to form openings extending from each end of 60 the bearing toward the middle thereof but not necessarily the full length of the bearing. The side edges 5, 5' of each opening are inclined upwardly and outwardly to form cams in a manner which will pres- 65 ently appear.

To assemble the clasp one of the parts is grasped in each hand and the divided lower side of the attaching loop where the pintles are formed is pressed against one of the 70 cam-shaped edges 5' on one side of the bearing causing the ends 6, 6' of the pintles to be sprung apart in a direction transversely to their axis, so that, by a lateral movement of the parts relatively to each other, the 75 edge 5' of the bearing sleeve is passed between the ends of the pintles causing one pintle to enter the sleeve and the other pintle to slide along its outside wall as shown in Fig. 3. The sliding of the parts one on 80 the other is continued and the parts folded toward each other until the outside pintle 85 is opposite the opening 4 and its end 6 passed over cam-shaped edge 5. When the parts have assumed this position the outside pintle 90 2 will snap over the edge 5 of the opening 4 into the bearing. On account of the attaching loop, which has been distorted by the spreading of the pintles, resuming its normal shape, the parts now having assumed 95 the position shown in Fig. 4. By now turning up the attaching loop, that is by folding the loops so that they will both be disposed in the same plane, the shoulder 3' will engage the cam-shaped edge 5' thereby caus- 100 ing the parts to slide laterally on each other until the shoulder 3' clears the end of the bearing and can swing backwardly and forwardly in its normal position. In this manner the pintles may be quickly slipped into 105 their bearings by a simple hand-operation.

In assembling my device in the manner above described not only the expense of the presses or other machinery usually employed for this purpose is eliminated, but it enables 110

the assembling to be done outside of the factory where the metal parts are made and further it enables the separate parts to be made in different factories, so that one concern 5 may furnish the sheet metal parts and another concern the wire parts and a third concern assemble the parts. It should be further noticed that should the occasion arise for disassembling the parts this operation 10 may also be performed by folding the parts toward each other and slipping either one of the pintles over the adjacent cam edge out of the bearing and sliding the parts laterally. Of course it is obvious that when the 15 attaching loop is made of sheet metal and the button loop is made of wire the former may carry the bearing and the latter the pintles.

While I have herein described my invention 20 as applied to button clasps for hose supporters yet the same may be embodied in any articulated metal mountings for running webbing which may fairly come within the scope of the appended claims.

25 Having now described my invention what I claim and desire to protect by Letters Patent is:

1. A metal mounting for running webbing comprising two articulated members one of 30 which is provided with a sleeve having a lateral opening and the other member with inwardly projecting pintles and abutting shoulders at the outer ends of said pintles, the said pintles being journaled in said sleeve 35 and the said lateral opening extending from one end of said sleeve toward the middle

thereof and having a cam-shaped edge for causing the parts to slide laterally relatively to each other when one of the said shoulders is engaged by said cam-shaped edge and the 40 parts are folded away from each other.

2. A metal mounting for running webbing comprising two articulated members one of which is provided with inwardly projecting pintles and the other member with a sleeve 45 having lateral openings extending inwardly from each end thereof toward the middle, the said openings having cam-shaped edges for causing the parts to slide laterally relatively to each other when one of said parts 50 is engaged by one of said edges and the two parts are folded away from each other.

3. A button clasp comprising an attaching loop bent up out of a single piece of wire the extremities of which terminate in 55 inwardly projecting pintles and abutting shoulders at the outer ends of said pintles, and a sheet metal button loop provided with a bearing sleeve in which said pintles are journaled, the said bearing sleeve being 60 provided with lateral openings extending from each end of the bearing sleeve toward the middle thereof and having upwardly and outwardly inclined edges whereby, when one of said shoulders is engaged by one of said 65 edges and the two loops are folded away from each other, the pintles will slide into their normal positions in the bearing.

In testimony whereof I have hereunto set my hand this 8th day of November 1918. 70

WILLIAM B. RUNK.
